UNITED STATES PATENT OFFICE

ROBERT HUDSON WAGER, OF JERSEY CITY, NEW JERSEY.

LATHER-FORMING PROCESS.

Original application filed March 15, 1922, Serial No. 544,059. Divided and this application filed March 13, 1924. Serial No. 699,133.

To all whom it may concern:

Be it known that I, ROBERT HUDSON WAGER, a citizen of the United States, residing at Jersey City, in the county of Hudson and State of New Jersey, have invented certain new and useful Improvements in Lather-Forming Processes; and I do declare the following to be a full, clear, and exact description of the invention, such as will enable others skilled in the art to which it appertains to make and use the same.

In barber shops and similar establishments, it was formerly customary to mix shaving lather in a mug by means of a brush and to repeatedly use the same brush and mug when shaving different patrons. For reasons of sanitation, this is very objectionable and it is the object of my invention to provide an improved process of forming the lather, which will dispense with the use of the mug and brush, yet will produce a lather of a thick creamy consistency, essential to proper shaving.

The present application forms a division of a prior U. S. application, S. N. 544,059, filed March 15, 1922, and in the accompanying drawing, I have illustrated an apparatus disclosed by said prior application, for carrying out the process covered by the present case, it being understood, however, that numerous other apparatuses can be used to advantage.

Figure 1 of the drawing illustrates a vertical sectional view, partly in elevation, of the apparatus.

Figs. 2 and 3 are sectional views as indicated by lines 2-2 and 3-3 of Fig. 1.

Fig. 4 is an elevation of a somewhat different form of apparatus.

In one aspect, my invention may be described as consisting in effecting contact of a fluid under pressure, preferably air, with a soapy liquid, and by fluid pressure, forcing the co-mingled liquid and fluid to ooze through screening means, preferably a plurality of screens until a thick creamy lather suitable for shaving is formed. Preferably after effecting contact of the soapy liquid and fluid under pressure, they are converted into minute cells by jointly forcing them through initial screening means. Then, these minute cells are converted into a thick creamy lather, by forcing them through ad-

ditional screening means, in most instances formed of a plurality of screens.

I have found that excellent results are obtainable by first forming soap bubbles and by forcing these bubbles against screening means with no liquid other than their vesicles. Preferably the bubbles are formed by aerating a soapy liquid in a closed container and the air pressure in this container is used to force the bubbles against the screening means which converts them into the creamy lather.

The apparatus shown comprises a container 1 having a water inlet 2, and a supporting platform 3 for a soap cake 4 showing soap being preferably used. On its lower side, the platform 3 is formed with a hollow attaching neck 5 and with substantially radial ribs 6, the neck being formed with air ports 7 between said ribs. The neck 5 is threaded into the bottom of the container 1 and communicates with an air port 8 in a neck 9 extending downwardly from said container. In Fig. 1 the neck 9 is coupled by a valve body 10 to a compressed air tank 11, while in Fig. 4 which constitutes the preferred construction, said neck is connected with a tube 12 leading from a hand bulb 13 by which the air is forced into the soap and water compartment. It will be obvious that when using a common hand bulb as shown at 13, no very great superatmospheric pressure can be produced. A suitable check valve 14 is shown in the neck 9 and when this neck is connected to an air tank, a valve 14^a is used to control the passage of air into the container 1.

At 15, a cap is shown for the container 1, said cap having a central recess 16 and an elongated passage 17 around the same, said recess being in communication with the container 1. One end of the passage 17 communicates with the recess 16 through a port 18 and the other end of said passage discharges into a spout 19 with which the cap 15 is provided. Discharge ports 20 are shown in the spout 17, but are not essential.

Between the recess 16 and the interior of the container 1, a screen 21 has been shown, and across the passage 17, additional screens 22 have been illustrated, in spaced relation.

The necessary soapy liquid is formed

(when using the apparatus shown) by placing a soap cake 4 on the platform 3 and partly filling the container 1 with water. The water compartment is preferably of 5 such a size as to accommodate only a small amount of water. Preferably the amount of water employed at a single filling, is only sufficient to create enough lather for one shave, and with this small amount of water, 10 the device can be tilted without causing the water to pour (as liquid) out through the lather outlet passage. Warm water is preferably used. Air under low pressure is then brought into contact with the soapy liquid 15 by admitting it through the port 8, and the construction shown will cause the air to whirl the water around the soap cake to form a soapy liquid of the desired quality. Effecting contact of the liquid and air by 20 aerating the former, in the foregoing or any adequate manner, will co-mingle the liquid and air and form soap bubbles in the container, and the accumulating air pressure in this container is utilized to dis- 25 charge the co-mingled air and liquid through the screening means by which it is converted to a thick creamy lather. When the co-mingled air and liquid is forced through the initial screen 21, it is more in- 30 tamately mixed and converted into minute cells and when these cells are forced along the passage 17 and through the additional screening means 22—22, they are converted into a thick creamy lather which oozes from 35 the spout 19 and may be taken on the hand and thereby applied to the face, or the lather can flow from the spout 19 directly upon the face, without the necessity of using a brush.

40 I claim:

1. A process of forming a thick creamy 45 shaving lather consisting in effecting contact of an undissolved gas under pressure with a volume of a soapy liquid, the gas and liquid being in such proportions as to form bubbles, and repeatedly screening the co-mingled liquid and gas under the influence of such a degree of gas pressure as can readily be produced by squeezing a hand bulb, 50 until a thick creamy lather suitable for shaving purposes is obtained.

2. A process of forming a thick creamy 55 shaving lather consisting in aerating a saponaceous liquid with a current of undis- solved air in such proportion as to form

soap bubbles, and repeatedly screening the bubbles under the influence of such a degree of air pressure as can readily be produced by squeezing a hand bulb, until a thick creamy lather suitable for shaving purposes 60 is obtained.

3. A process of forming a thick creamy 65 shaving lather from soap bubbles which comprises the step of repeatedly screening the bubbles under such an amount of gas pressure as can readily be produced by squeezing a hand bulb, until a thick creamy lather suitable for shaving purposes is obtained.

4. A process of forming a thick creamy 70 shaving lather from soapy bubbles which comprises the step of repeatedly screening the bubbles with no liquid other than the vesicles of said bubbles, until a thick creamy lather suitable for shaving purposes is ob- 75 tained.

5. A process of forming shaving lather which comprises maintaining a cake of soap of a kind suitable for use as shaving soap in contact with an aqueous liquid, passing air 80 under pressure only slightly above atmospheric, upwardly through such liquid to form a mass of bubbles and repeatedly screening such bubbles until a smooth creamy shaving lather is produced. 85

6. A process of forming shaving lather which comprises maintaining a cake of soap of a kind suitable for use as shaving soap, in contact with an aqueous liquid, passing air under pressure only slightly above atmospheric, upwardly through such liquid to form a mass of bubbles and repeatedly screening such bubbles alone, and substantially without other liquid than the walls 90 of the bubbles themselves, until a smooth creamy shaving lather is produced. 95

7. A process of forming shaving lather which comprises maintaining a cake of soap of a kind suitable for use as shaving soap, in contact with an amount of an aqueous liquid 100 which is not many times more than the amount needed for a single shave, passing air under pressure only slightly above atmospheric, upwardly through such liquid to form a mass of bubbles and repeatedly screening such bubbles until a smooth creamy shaving lather is produced. 105

In testimony whereof I have hereunto affixed my signature.

ROBERT HUDSON WAGER.
